FIG. 1

FIG. 2

FIG. 3

FIG. 4

FIG. 5

FIG. 6

FIGURE 1 is a perspective view of a mirror clip showing my new design;

FIGURE 2 is a side elevation of the same;

FIGURE 3 is a front elevation of the same;

FIGURE 4 is a top plan view of the same;

FIGURE 5 is a rear elevation of the same; and

FIGURE 6 is a bottom plan view of the same.

The top of my mirror clip is characterized by four facets of approximately equal area which slope away from a common central point in four different planes. Each end of the mirror clip has two approximately rectangular facets which form an obtuse dihedral angle.

I claim:

The ornamental design for a mirror clip, as shown and described.
